CLAIM

The ornamental design for a decanter, substantially as shown and described.

DESCRIPTION

FIG. 1 is a side elevational view of a decanter showing my new design, the opposite side being a mirror image thereof;

FIG. 2 is a front elevational view with the closure removed, the rear view being substantially the same in appearance except that the simulated rope is not seen at the bottom portion;

FIG. 3 is a bottom plan view;

FIG. 4 is a top plan view with the closure in place;

FIG. 5 is a sectional view taken on the line 5—5 of FIG. 2.
